G. CLAUSING

LAST

Filed May 18, 1925

Patented Jan. 26, 1926.

1,570,613

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed May 18, 1925. Serial No. 31,097.

To all whom it may concern:

Be it known that I, GEORGE CLAUSING, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to lasts and in particular to a last which will stay in either expanded or collapsed position.

In detail, it is my object to provide a last 15 which will have a combined lever and spring and in which the last parts will be connected together by a link, the link being connected to the last part on one side by an anchor pin and on the other side to the lever which carries the spring and is connected pivotally 20 to another anchor pin.

It is a further object to have the spring engage with the first mentioned anchor pin.

It is an additional object to have the pivotal point of connection of the link to 25 the lever and the anchor pin on which the link is pivoted and against which the spring abuts so arranged that a line drawn between their centers will pass over the center of movement of the last parts when they are 30 moved from one position to the other.

Referring to the drawings:

Figure 1 is a side elevation partially in section, disclosing the link, lever, and spring mechanism of the last;

35 Figure 2 is a plan view partially in section of the link, lever and spring mechanism mounted on the anchor pins which are broken away and shown only for a portion of their length.

40 Referring to the drawings in detail, 1 is a toe part having a cut away portion or groove 2, cut in its instep portion, such groove having an outer open end along the rear face 3 of the toe part. Transversely 45 located across this open mouth of the cut away portion 2 and across the rear face of the last part 1 is a semi-circular groove or socket 4 to receive the transverse cylindrical projecting bearing member 5 which cooper-

50 ates with the socket to form a knuckle joint. The forward last face 6 of the heel part of the last is cut away so as to permit the last parts to collapse. The lower adjacent faces of the last parts designated 8 and 9 engage when the last is in its expanded po-

sition below the knuckle joint to limit the extent of the expansion. The heel part of the last is provided with a cut away slot 10 for receiving the spring and link. Transversely of this cut away portion is located 60 the heel part anchor pin 11 upon which is mounted the rear end of the links 12 which connects the last parts together. These links are spaced to receive between them the lever and spring hereinafter mentioned. These 65 links proceed forwardly to a point where they are pivoted on the stud 13. This stud 13 is carried by the lever 14, one end of which is pivoted on the anchor pin 15 in the toe part of the last which crosses the lower 70 part of the slot 2 in the toe part of the last. This lever above the pin 13 proceeds forwardly and rearwardly in a gentle curving arm forming a lever arm 16 which terminates above the anchor pin 11 and descends 75 downwardly in the form of a hook 17 around the forward face of the anchor pin 11.

It will be observed that the center of movement of the last part is primarily about the point 18 and that a line drawn between 80 the center of the anchor pin 11 and the center of the pin 13 will pass over this center 18 when the parts are moved from one position to the other, thus maintaining under spring tension the parts in either expanded 85 or collapsed position. A line drawn between the anchor pins 11 and 15 will not, however, pass over this center point when the parts are moved.

It will be observed that due to the use of 90 the lever 14 and the lever arm 16 it is possible to get considerable leverage of the spring 17 and to place that spring solely within the heel part and at the point where it will have the maximum effect. The lever 95 and spring are prevented from turning by being embraced between the links 12 as will be more clearly seen in Figure 2.

It will be understood that I desire to comprehend within my invention such modifications as may be necessary to adapt it to varying conditions of use.

Having thus fully described my invention, what I claim as new and desire to secure by Letters Patent, is:

1. In a last, a toe part and a heel part adapted to rock one on the other, a link joining said parts, an anchor pin in one last part supporting the link at one end, a lever pivotally supporting the link at its 110

other end, an anchor pin in the other last part for supporting said lever, and means attached to said lever projecting from said lever in one last part to a point 5 within the other last part for supporting a spring, and a spring engaging said first mentioned last part.

2. In a last, a toe part and a heel part adapted to rock one on the other, a link 10 joining said parts, an anchor pin in one last part supporting the link at one end, a lever pivotally supporting the link at its other end, an anchor pin in the other last part for supporting said lever, and means attached 15 to said lever projecting from said lever in one last part to a point within the other last part for supporting a spring, a spring engaging said first mentioned last part, said engagement being effected through the 20 spring bearing upon the anchor pin in said part.

3. In a last, a toe part and a heel part adapted to rock one on the other, an anchor pin transversely arranged in each of said 25 parts, a link pivoted on one of said anchor pins, a lever pivoted on the other of said anchor pins, said lever being projected normally forwardly over the anchor pin, said link being connected to the end of said lever 30 at its forwardmost portion, a suspension member extending from the end of the lever rearwardly to a pin adjacent the other last part, and a spring suspended therefrom engaging with the first mentioned anchor pin. 35

35. 4. In a last, a toe part and a heel part adapted to rock one on the other, an anchor pin transversely arranged in each of said parts, a link pivoted on one of said anchor pins, a lever pivoted on the other of said anchor pins, said lever being projected normally forwardly over the anchor pin, said link being connected to the end of said lever at its forwardmost portion, a suspension member extending from the end of the 40 lever rearwardly to a pin adjacent the other last part, and a spring suspended therefrom engaging with the first mentioned anchor pin, said parts being so arranged that a line drawn from the center of the first anchor pin to the point of pivotal connection of the link to the lever will pass over the center of movement of the last parts when they move from one position to the other. 45

55. 5. In a last, a toe part and a heel part adapted to rock one on the other, an anchor pin transversely arranged in each of said parts, a link pivoted on one of said anchor pins, a lever pivoted on the other of said anchor pins, said lever being projected normally forwardly over the anchor pin, said link being connected to the end of said lever at its forwardmost portion, a suspension member extending from the end of the lever rearwardly to a pin adjacent the other last 60 part, and a spring suspended therefrom engaging with the first mentioned anchor pin, said parts being so arranged that a line drawn from the center of the first anchor pin to the point of pivotal connection of the link to the lever will pass over the center of movement of the last parts when they move from one position to the other. 65

gaging with the first mentioned anchor pin, said suspension member being resilient.

6. In a last, a toe part and a heel part having an intermediate knuckle joint to enable them to rock one upon the other and cut away portions opening towards each other, links arranged in said cut away portions, an anchor pin located in each of said last parts passing through said cut away portions transversely thereof, said links being pivoted on one side upon one of the anchor pins and at the other upon a transverse pin carried by levers, a transverse pin, levers carrying said pin, said levers being pivoted on the other of said anchor pins, and a rearwardly extending arch shaped suspension member carrying an S-shaped spring at its free end adapted to engage with the first mentioned anchor pin. 70 75

7. In a last, a toe part and a heel part having an intermediate knuckle joint to enable them to rock upon one another and cut away portions opening towards each other, links arranged in said cut away portions, an anchor pin located in each of said last parts passing through said cut away portions transversely thereof, said links being pivoted on one side upon one of the anchor pins and at the other upon a transverse pin carried by levers, a transverse pin, levers carrying said pin, said levers being pivoted on the other of said anchor pins, and a rearwardly extending arch shaped suspension member carrying an S-shaped spring at its free end adapted to engage with the first mentioned anchor pin. 80 85

35. 4. In a last, a toe part and a heel part adapted to rock one on the other, an anchor pin transversely arranged in each of said parts, a link pivoted on one of said anchor pins, a lever pivoted on the other of said anchor pins, said lever being projected normally forwardly over the anchor pin, said link being connected to the end of said lever at its forwardmost portion, a suspension member extending from the end of the lever rearwardly to a pin adjacent the other last part, and a spring suspended therefrom engaging with the first mentioned anchor pin, said parts being so arranged that the point of connection of the links with the first anchor pin and the point of connection of the links with the lever are so located that a line drawn between their centers will pass over the center of movement in the knuckle joint of the last parts when they are moved from one position to the other. 100 105

8. In a last, a toe part and a heel part having an intermediate knuckle joint to enable them to rock one upon the other and cut away portions opening towards each other, links arranged in said cut away portions, an anchor pin located in each of said last parts passing through said cut away portions transversely thereof, said links being pivoted on one side upon one of the anchor pins and at the other upon a transverse pin carried by levers, a transverse pin, levers carrying said pin, said levers being pivoted on the other of said anchor pins, and a rearwardly extending arch shaped suspension member carrying an S-shaped spring at its free end adapted to engage with the first mentioned anchor pin, said parts being so arranged that the point of connection of the links with the first anchor pin and the point of connection of the links with the lever are so located that a line drawn be- 110 115 120 125 130

tween their centers will pass over the center of movement in the knuckle joint of the last parts when they are moved from one position to the other, said links being so arranged 5 on either side of the said lever and said S-shaped spring as to prevent the lever and spring from turning upon their supports laterally.

9. In a last, a toe part and a heel part 10 adapted to rock upon one another, means comprising a non-yielding link and lever arm to connect said parts together as they rock one

upon the other, yielding means attached to and forming an integral part of said lever arm engaging the heel part tending to maintain said parts in either expanded or collapsed position, said link and lever arm forming a lever arrangement for increasing the effect upon said yielding means on the movement of the parts from one position to 20 the other.

In testimony whereof, I affix my signature.

GEORGE CLAUSING.
